[57] ABSTRACT

This invention transfers a graphic image from a reduced film image to the appropriate location on a film photo-composed page. The preferred embodiment of this invention consists of an aperture card (microfilm mounted on computer punch card) handling system for feeding and positioning the reduced image film; an image copying system which projects light through the reduced image and focuses it onto the correct horizontal position on the output photocomposed page; and a system for accurately positioning the photocomposed page film.

1 AUTOMATIC PHOTO-COMPOSER

This invention provides a method whereby graphic material can be placed on a photo-composed page for the purpose of photo-composition. The input to this device is a reduced film copy of the graphic image labeled by its location on the page to produce photo-composed pages with the graphic material properly positioned on the page.

There are presently many devices for photo typesetting of text material which can photo-compose the text of a page. At present there is no system of automatically merging graphics material with the text. This invention accomplishes just that.

Among the objects of the present invention is the provision of an automatic photo-composer for use in adding graphic images to a previously photo-typeset film, which will accurately and precisely position the graphic images onto the proper pages on the film. This device is controlled by a minicomputer utilizing punched computer cards having a film mounted in an aperture in the card with the desired image on the film. The film image is projected onto the typeset output film.

Another object of the present invention is the provision of an automatic photo-composer having an image correction system which can correct error from film mounting and operative card handling. The image correction system utilizes a semi-conductor correcting target with a photocell matrix receiving a hairline light beam from the aperture card. The photocell matrix controls motor reed relays which will cause movement of one or more mirrors in the image projection system to cause movement of the image up or down, right or left, or rotate clockwise or counterclockwise, and then indicate when the image position is correct.

A further object of the present invention is the provision of an automatic photo-composing device with a system to position the image in the proper horizontal column. This system utilizes a series of pairs of mirrors which may be inserted into the image light beam to change the light path depending on which column the image is to be positioned as controlled by the punched aperture cards.

The present invention also comprehends the provision of an electronic control system for the automatic photo-composing device which will accurately control the positioning and projection of the graphic images from the aperture cards to the typeset film.

Further objects are to provide a construction of maximum simplicity, efficiency, economy and ease of assembly and operation and such further objects, advantages and capabilities as will later more fully appear and are inherently possessed thereby.

In the drawings:

FIG. 1 is a schematic diagram of the major components of the system.

FIG. 2 shows the output film where the graphic images have been copied thereon.

FIG. 3 shows an input aperture card containing a graphic image.

FIG. 4 is a schematic showing of the image correction system.

FIG. 5 is a schematic showing of the electronic and electrical subsystems of the invention.

FIG. 6 is a schematic showing of the horizontal column beam repositioning system.

2

FIGS. 7a-7e show the hairline photo-cell matrix device and the projection of various hair lines on it.

FIG. 8 is a showing of a sample film input to and completed film output from this device, and image input cards for the film input.

FIG. 9 is a schematic showing of the continuous horizontal repositioning apparatus.

An example of the use of this device would be in the setting of a yellow pages section of a phone book. The text would be set by a photo-typesetting device with white space left for ads, the input page film in FIG. 8 being an example. As a computer program produces the photo-type-setting magnetic tape for the phototypesetter, it would also produce a tape containing the identification number, location, and magnification of each ad in the book. Then, aperture cards (see FIG. 3) containing the reduced negative copy of the ad 112, and the punched ad identification number 107, are read into a computer which then punches the page on which the ad is to occur at 108, the leading from the top of the page at 109, the column in which the ad starts at 110, and a code indicating what magnification is to occur at 111. These cards are then sorted on the basis of page and leading values and fed into the photo-composer. The photo-composer, the subject of the present invention, then copies the reduced film image onto the appropriate location on the typeset film. The end result is a complete page, similar to the output film shown in FIGS. 2 and 8.

The system disclosed in FIGS. 1 through 6, illustrates one embodiment of this invention. In this embodiment the image is transferred optically from the reduced film input to the output film. The primary components of this system are: 1) a system for handling the output page onto which film images are copied; 2) a system for feeding, reading, and positioning aperture cards; and 3) a system for copying the image from the aperture card to the output film.

40 The output film handling system feeds film from a normal photo-typesetting machine past the graphic imaging system, and to a take-up reel.

Referring to FIG. 1, the typeset output film 1 is fed from roll 2 contained in film cartridge 3 over sprockets 4, 8 and roller 14 to be taken up on take-up reel 15 in cartridge 16. A DC motor 19 is actuated whenever the film loop 5 gets so small that micro-switch 7 is closed. Thereafter motor 19 drives the sprocket 4 playing out film until the film contacts micro-switch 6, stopping motor 19.

55 Stepping motor 20 operates sprocket 8 which keeps the film taut over metal plate 22. The stepping motor allows for very accurate positioning of the film 1 and, in conjunction with metal plate 22, keeps the film taut where the image beam 18 contacts the film. This allows for very fast and accurate positioning of the film.

Before the image beam 18 contacts the film 1, a portion of the beam is blocked by shield 10 which marks portions of the input film image containing correction and identification marks. After passing through the shield the image passes through a removable photographic line screen 9 and then onto film 1. When images requiring half-tone processes are to be copied, screen 9 is in place in order that halftone images are projected onto the film. Screen 9 is removed for line work or other graphic material not requiring halftone screening.

Microswitch 17 is designed to determine the beginning of pages on the film 1. With reference to FIG. 2, several leading photo-typesetting machines put notches 76, 77 on the output film to indicate the start of page positions. Whenever one of these notches 76 or 77 passes under microswitch 17, a pulse is sent to the computer indicating that a new page is positioned under the image beam 18. Since the computer system pulses stepping motor 20 and reads page indications from micro-switch 17, an internal counter indicates what portion of film is positioned under the image screen.

As the film passes across metal plate 22, it passes under the crosshair projection lamp 94. This lamp is turned on when the appropriate portion of film 1 passes under it to copy a printer's crosshair onto the film for use for later alignment. As film loop 11 increases, micro-switch 12 is closed activating motor 21, causing take-up reel 15 to turn, winding up film until micro-switch 13 is closed.

CARD HANDLING

The card handling system feeds the cards, reads the punched holes, physically positions the cards, and then optically positions the images.

The card feeding process (see FIG. 1) takes the cards from the input hopper 24, passes them under rollers 25 and under the card reading head 26 to the film cleaning head 27, and then under the card imaging system 64 where the image is copied onto the output film. After the images have been copied, the cards are fed into card hopper 28. It is important to note that the punched information of the second card has been read before the first card's image is copied with the punched information of both cards kept in the device's computer memory. The purpose of having the information for both cards stored will be explained in the image copying system.

For fuller explanation, the processing of one aperture card will be followed through the card handling system. On the first feed cycle the card is fed onto the path 29 from the input hopper 24. On the second feed cycle the card moves under the card reading head 26. At this point, the punched data is read from the card. During the third feed cycle, the card passes under the film cleaner 27 and is positioned under the card imaging system 64 for image copying. When the card blocks the light on photocell 30 the card feed mechanism is braked to stop the card immediately. At this point physical positioning of the aperture card is complete.

IMAGE CORRECTION

Because of inaccuracies in mounting the 35 mm. film on the aperture card and the exaggeration of these errors by the magnification process, each input image must be repositioned. FIG. 3 shows a typical input aperture card 34 with an aligning crosshair 106 photographed onto the film. By accurately positioning this crosshair, the film image is correctly aligned for projection and errors in mounting the film on the aperture and in card positioning are compensated for.

The image correction system (see FIGS. 1 and 4) projects the reduced film image onto two sets of front surfaced mirrors or Dove prisms which reposition the image vertically, horizontally and rotationally. Light from lamp 31 passes through condensing lens 32 and

the reduced film image 33, projecting the image onto reflecting mirrors or Dove prisms 35 and 41. The light beam then passes through a projecting lens 42 and a beam splitter 43. A portion 47 of the beam passes through a second lens 44 to a semi-conductor correcting target 45. A front view of semi-conductor target 45 is shown enlarged in FIG. 7a.

The image correction circuit consists of three DC motors and a photocell matrix. The photocell matrix on target 45 provides seven output lines which drive each motor forward or in reverse and indicate when the correction is complete. FIG. 7a is an enlarged view of the photocell matrix and indicates the output lines. These output lines are coupled to electronic or electromechanical switches which activate the image positioning motors. Current will not energize a motor unless the hairline light beam crosses two of the photocell sections that control the motor.

FIGS. 7b—7e explain in greater detail just how the hairline is positioned. The dotted line represents light from the film hairline. The light in FIG. 7b crosses photocells 65, 66, 70, 72. This causes the "move left" switch to close. Referring to FIG. 4, motor 115 is actuated to rotate pinion gear 114 and move rack gear 113 and therefore motor 37 and mirror or Dove prisms 35 to the left, thus causing the hairline to move to the position shown in FIG. 7c. The hairline in FIG. 7c falls on photocells 65, 66, 70, 71. Photocells 70 and 71 close the "rotate counter-clockwise" switch and actuate motor 37 to rotate mirror or Dove prisms 35, while motor 115 continues to move the mirror or Dove prisms 35 to the left due to light on photocells 65 and 66. In FIG. 7d, the hairline crosses only photocells 66 and 67 and the vertical portion of photocell 73. The "move up" switch is thereby closed to actuate the motor 46 to rotate pinion gear 120 and move rack gear 121, thus moving mirror or Dove prisms 41 forward and causing the hairline to take the position shown in FIG. 7e. When the hairline crosses all of photocell 73 the current closes a switch indicating to the minicomputer control circuitry that positioning is complete.

SHUTTER CONTROL

FIG. 4 shows the shutter 83 which normally blocks light beam 18. The minicomputer switches the shutter 83 on and off to either block or allow the light beam 18 to pass to light sensitive recording member 1.

HORIZONTAL COLUMN REPOSITIONING SYSTEM

The horizontal column repositioning system shown in FIG. 6 consists primarily of sets of mirrors arranged to project the graphic image to one of a set of horizontal locations on the output film. As indicated in FIG. 6, the distance the light beam travels from shutter 83 to the light sensitive recording member 1 (output page film) is held constant in order to keep the image focused while it is being horizontally repositioned.

Each set of mirrors consists of two front surface mirrors 56 and 57, 54 and 55, 52 and 53 or 50 and 51 mounted equidistant from an apex of a guide 87, 88, 89 or 90, respectively. 87, 88, 89 mirror guides are installed in mirror guide runners 92 and 93. The mirror guide 87 for column one is positioned and fastened so that the center of mirror 56 intersects light beam 18. With mirrors 56 and 57 positioned on guide 87 equidistant from the apex 91, the graphic image can be pro-

jected so that its left edge falls on the left edge of column one on the light sensitive recording member 1.

Horizontal repositioning for columns two, three, and four is handled basically the same way except that mirrors 50, 52 and 54 are retractable. Mirrors 50, 52 and 54 are mounted on solenoids 84, 85 and 86, respectively, so that they reflect the light beam only when their appropriate solenoid is activated. In FIG. 6, mirror 52 is shown extended. In this case, light beam 18 is reflected down light path 60 and horizontally displaced so that the left edge is located on the left edge of column three. Light beam 18 will travel down light path 58 if no solenoids are activated; path 59, if solenoid 86 is activated; path 60, if 85 is activated; and path 61, if solenoid 84 is activated. Thus, by activating solenoid 84, 85 or 86, the image can be projected to any of the predetermined horizontal positions.

CONTINUOUS HORIZONTAL REPOSITIONING SYSTEM

In situations where the graphic images are not set in column format, a moving mirror pair shown in FIG. 9 is used. A minicomputer pulses stepping motor 100 which in turn rotates spur gear 99 moving rack gear 98. This in turn moves the pair of front surfaced mirrors 97, which deflect light beam 18. This system has the advantage over the previously described system in that the beam can be positioned horizontally anywhere on the page. It is, however, considerably slower than the horizontal column repositioning system. When this system operates in column format, the computer has stored in it a set of increments for each column so that the aperture card need only contain a column number for horizontal positioning.

COLOR FILTERING

In order to produce full color images for printing, four copies of the original graphic material must be made, one each for yellow, magenta, cyan and black. To accomplish this, four output page films are made. Referring to FIG. 4, for copying the black portion of the image, filter 62 is a modified filter. With this filter in place the black portions of the image are transferred onto the phototypeset output film giving an end result similar to that in FIG. 2. After all the cards have been run through for the black portion of the image, the aperture cards are run through three more times with the respective filters in place to produce yellow, magenta and cyan portions of the image on bulk film which is spaced to the appropriate location for the image to be copied onto it.

ELECTRONIC CONTROL SYSTEM

Although a hard wired system could accomplish the control of the equipment described, the preferred embodiment of this invention employs a minicomputer to increase its versatility. Inputs to the minicomputer (FIG. 5) are data from card reader 26, photocell 30, crosshair correction indicator 73, page sensing switch 17, film sensing switch 75, and a teletype input. Outputs from the minicomputer control the card feeding system, the image correction system, magnification lens system 63, shutter 83, mirror controlling solenoids 84, 85, 86, stepping motor 20, printers hairline projector 94, and a teletype output.

The controlling circuits and their functions can be illustrated by following the procedure for setting a two

page book with three graphic images. FIG. 8 shows the input aperture cards 79, 80 and 81, input typeset page film 78, and the output page film 82. FIG. 5 schematically shows the controlling operation.

To initiate operation, 1) input film 78 which was previously typeset on a conventional photo-typesetting machine is mounted in the page film handling system; 2) the three aperture cards are loaded into card hopper 24; 3) power is turned on; and 4) the number of the first page is typed into the teletype. The minicomputer then pulses stepping motor 20 until the first page indicator notch 76 is sensed by switch 17. At this point the internal page film counter 104 is set to the page number that was typed in, in this case page 1, with vertical leading set at zero. The computer turns on the printer's hairline projector 94 (FIG. 1) which copies a hairline 95 (FIG. 8) onto the output film 82. The printer's hairline is copied to allow for later alignment of printing plates, particularly in the use of color.

The card handling system feeds cards 79, 80 and 81 such that when card 79 is at the imaging station 64, card 80 has passed under the reading head 26 and is ready to be fed into the imaging station, and card 81 has been fed and is ready to be fed past reading head 26. The punched information from card 79 was read by reading head 26 and stored in the image card storage indicator 103 of the minicomputer. The punched information of card 80 is stored in the buffered card storage indicator 102.

At this point the normal operation of the device has begun. When photocell 30 is blocked by card 79 at the imaging station, the computer switches on the optical hairline correction system. The information from the image card storage column indicator selects which solenoid 84, 85 or 86 in the horizontal repositioning system is to be activated to position a particular mirror in light beam 18. Or, in the continuous column repositioning system, the number of pulses the stepping motor 100 receives.

Lens system 63 is operated so the lenses are in the correct position for the magnification code specified on the image card. When the image is correctly positioned, as indicated by cross hair indicator 73 and the appropriate column mirror is positioned, an image-ready-to-be-copied switch 122 is set in the computer.

During all of this time, the computer has been going through a page film advance cycling procedure which consists of the computer pulsing the stepping motor 20, incrementing the internal page film leading counter 104, and comparing the internal page film counter 104 with the page and leading information from the image card storage indicator 103. If the film page number and/or leading is larger than the information from the image card storage indicator 103, the machine stops and an alarm rings. If smaller, the computer pulses motor 20, increments the counter 104 and compares again.

When the page and leading values of the image card storage indicator 103 and internal page film leading counter 104 are equal, the copy cycle begins. First the image-ready-to-be-copied switch 122 is checked continuously until it indicates ready. The shutter 83 is then opened to allow light beam 18 to pass through for a prescribed period of time. The image is now in proper position on the output page film.

The graphic material on the aperture card 79 film was a 4 column by 3 inch graphic image in this exam-

ple. The graphic image was positioned onto the page so that the left edge of the image aligns with the left edge of column 1, and the top of the graphic image falls at a leading of 3.50 inches from the top of the page, as indicated by punched information from the image card. By positioning the left and top edge of the graphic image, its location is fully determined. The area of the page film receiving light is determined by the original material. In this way a three column by 2 inch graphic original will be a three column by 2 inch graphic on the page film if no magnification is indicated.

If magnification is indicated the minicomputer outputs pulses to the lens system 63 which repositions the lenses to the desired magnification. Magnification is normally done only when the continuous horizontal repositioning system is used. The minicomputer calculates the horizontal and vertical displacement that results from the magnification and inserts these corrected values in the image card storage indicator 103. With these corrected values the system works as previously described.

After the image from card 79 is copied, the machine feeds in a new card and prepares for copying it. After shutter 18 closes, the image-ready-to-be-copied switch 122 is turned off, the contents of the buffered card indicator are moved into the image card storage indicator, and the page film advance cycle is started. As the page film is advanced, page film notch 77 passes under page sensing switch 17. When the switch is closed the computer increments the internal page film page counter 104, resets the internal page film leading to zero, and turns on hairline projector 94 which copies a printer's hairline 96 onto the page film.

Since the next graphic image 80 is to appear in column 2 the computer activates solenoid 86, extending mirror 54 to cause the left edge of the graphic image to align with the left edge of column 2. The card image is then copied in the same manner as card 79, but on page 2 with a vertical leading of 2.10 inches and the left edge aligned with column 2's left edge.

The machine then cycles again and card 81's image is also copied. In this way a book of any length, with any number of pages (maximum 10,000) and any number of graphic images can be merged with type completely automatically.

When the minicomputer cannot continue, in situations such as a card jam, card out of order, too few cards, inability to position correcting crosshair, or end of page film, the machine stops, sounds an alarm to gain operator attention, and specifies the problem via the teletype.

This invention is also operable with any electrical or optical projection system, e.g., a television camera converting the film image to electrical signals and a cathode ray tube to convert the electrical signals to light which is then focused onto the film.

While the forms of apparatus herein described constitute preferred embodiments of the invention it is to be understood that the invention is not limited to these precise forms of apparatus, and that changes may be made therein without departing from the scope of the invention which is defined in the appended claims.

I claim:

1. An automatic photo-composing system for copying graphic images, line drawings and half-tones in either color or black and white from film copies of the desired images to the correct horizontal and vertical

location on a recording member, comprising a copying apparatus including a light sensitive recording member which may contain photo-typeset text or page indicator marks, means for positioning the graphic film images for copying them onto the recording member, means for projecting an image beam through the film image onto the recording member, means for intermittently moving the recording member relative to the image beam, and a correction system for correcting errors in positioning of the film comprising a photo-electric target receiving an indicator image from the film copy of the graphic image, and means to reposition the image beam from the film copy to the recording member to correct for horizontal, vertical and rotational errors to a standard position indicated by the target.

2. An automatic photo-composing system as set forth in claim 1, in which the correction indicator image is accurately positioned on the film copy of the graphic image to be copied by photographing the indicator image onto the film copy when the original graphic image is photographed thereon.

3. An automatic photo-composing system as set forth in claim 1, in which said repositioning means includes one or more rotating mirrors or Dove prisms and individual motors actuating the mirrors or Dove prisms for horizontal, vertical and rotational movement.

4. An automatic photo-composing system as set forth in claim 1, in which said target includes a photocell matrix providing seven matrix lines, and electrical activating means connected to said matrix lines to actuate the repositioning means.

5. An automatic photo-composing system as set forth in claim 1, in which said projection means includes an enlarging lens, a beam splitter dividing the image beam into two parts, one of which is projected onto the photo-electric target, and means to deflect the remainder of the beam to variable positions on the recording member.

6. An automatic photo-composing system as set forth in claim 1, including optical means for projecting the image beam with horizontal displacement onto the recording member.

7. An automatic photo-composing system for copying graphic images, line drawings and half-tones in either color or black and white from film copies of the desired images to the correct horizontal and vertical location on a recording member, comprising a copying apparatus including a light sensitive recording member which may contain photo-typeset text or page indicator marks, means for positioning the graphic film images for copying them onto the recording member, means for projecting an image beam through the film image, means for intermittently moving the recording member relative to the image beam, and means for projecting the image with horizontal displacement onto the recording member, wherein information indicating the position that the film image is to occupy on the recording member is coded onto the film containing the image or the mounting card therefor, the information being used by the apparatus to position the film image onto the recording member.

8. An automatic photo-composing system as set forth in claim 7, including a card hopper receiving the aperture cards, a card reading device under which each card is fed, and a projection system where each card is positioned such that light is projected through the film image of the aperture card.

9. An automatic photo-composing system for copying graphic images, line drawings and half-tones in either color or black and white from film copies of the desired images to the correct horizontal and vertical location on a recording member, comprising a copying apparatus including a light sensitive recording member which may contain photo-typeset text or page indicator marks, means for positioning the graphic film images for copying them onto the recording member, means for projecting an image beam through the film image, means for intermittently moving the recording member relative to the image beam, optical means for projecting the image beam onto the recording member, and beam deflection means including at least one pair of mirrors positioned in the image beam's path whereby the image is horizontally deflected with the focal length of the image beam remaining constant, and means to position the mirrors such that the light is deflected horizontally from the first mirror to the second mirror such that the angle of the second mirror has an angle of incidence with the image beam of 90° minus the angle of incidence of the beam with the first mirror.

10. An automatic photo-composing system as set forth in claim 9, in which one pair of mirrors intersect each other at and are secured to a rack, a pinion engaging the rack, and a motor actuating the pinion to move the rack and mirrors such that as the distance between the image source and the mirrors decreases, the distance the light beam travels between the two mirrors decreases in such a way as to decrease the horizontal displacement of the image while keeping the beam length from the film image to the light sensitive recording member constant.

11. An automatic photo-comprising system as set forth in claim 9, in which the mirror positioning means includes a pair of mirrors for each column on the page to be printed, a guide for each pair of mirrors with the mirrors mounted equidistant from the apex of the guide, each pair of mirrors being positioned on its guide to deflect the light beam to a desired column, one mirror of each pair adapted to be positioned in the initial path of the light beam, the first mirror for one column being stationary, and a solenoid for the first mirror of each additional pair to project its mirror into the initial path of the light beam and deflect the light beam to a column in a different horizontal position relative to said one column.

12. An automatic photo-comprising system for copy-

ing graphic images, line drawings and half-tones in either color or black and white from film copies of the desired images to the correct horizontal and vertical location on a recording member, comprising a copying apparatus including a light sensitive recording member which may contain photo-typeset text or page indicator marks, means for positioning the graphic film images for copying them onto the recording member, means for projecting an image beam through the film image, optical means for projecting the image beam onto the recording member, and a handling system for the light sensitive recording member including an input roll of the recording member, means for pulling the recording member off of the input roll to produce a loop, means to retain the recording member taut where the projected image beam contacts it, means to advance the recording member under the image beam, means to sense the beginning of a page on the recording member, a light shield to prevent unwanted portions of the image beam from contacting the member, and means for taking up the recording member after the member has passed through the image copying device.

13. An automatic photo-composing system for copying graphic images, line drawings and half tones in either color or black and white from film copies of the desired images to the correct horizontal and vertical location on a recording member, comprising a copying apparatus including a light sensitive recording member which may contain photo-typeset text or page indicator marks, means for positioning the graphic film images for copying them onto the recording member, means for projecting an image beam through the film image, means for intermittently moving the recording member relative to the image beam, an optical correction system for correcting errors in film repositioning comprising a photo-electric target receiving an indicator image, one or more rotating mirrors or Dove prisms acting to reposition the image to a standard position to copy the film image onto the recording member, motors actuating the mirrors and Dove prisms, and optical means for projecting the image beam with horizontal displacement onto the recording member including an enlarging lens, a device which splits the beam into two parts, one of which is projected through a lens to the photo-electric target, a film shutter and means to deflect the remainder of the beam to variable positions on the recording member.
